UNITED STATES PATENT OFFICE.

ALBERT RENTNER, OF HAMMOND, INDIANA.

CHUTE.

1,109,786.

Specification of Letters Patent.

Patented Sept. 8, 1914.

Application filed November 5, 1913. Serial No. 799,289.

To all whom it may concern:

Be it known that I, ALBERT RENTNER, a citizen of the United States, residing at Hammond, in the county of Lake and State 5 of Indiana, have invented certain new and useful Improvements in Chutes, of which the following is a specification.

This invention relates to chutes designed to facilitate the delivery of coal and other 10 material to the cellar of a building, and the object of the invention is to provide a strong and durable chute, and a novel closure therefor, together with certain improved structural details to be pointed out 15 in the following description, reference being had to the accompanying drawings, in which—

Figure 1 is a front elevation of the chute; Fig. 2 is a horizontal section on the line 2—2 20 of Fig. 1; Fig. 3 is a vertical section on the line 3—3 of Fig. 1; Fig. 4 is a side elevation of the chute, and Fig. 5 is an enlarged sectional detail of a hinge.

Referring specifically to the drawings, 10 25 denotes a rectangular metal frame which is mounted in a hole in the wall 11 of a building. The frame has an outstanding marginal flange 12, and between said flange and the side portions of the frame are anchoring lugs or webs 13. The flange fits against the outer surface of the wall 11. The frame 10 supports a sheet metal chute 14 having an inclined bottom. The chute is riveted, or otherwise secured to the frame, on the 30 35 outside thereof, behind the flange 12.

Associated with the chute 14 is a combined door and hopper comprising a front wall 15 and side walls 16. To the inner face of the wall 15, at the bottom, and adjacent 40 45 to the vertical edges thereof, are riveted, or otherwise secured lugs 17 having outstanding hinge-pintles 18, which latter work in oblong or elliptic apertures 19 in the side portions of the frame 10. The apertures are inclined in the direction of their greater dimensions, or major axes, the inclination being inward. On the inside of the frame 10, the top and side portions thereof have a rib 20 which is spaced from the front of

the frame a distance to accommodate the 50 wall or door 15, a rabbet 21 being thus formed in which the door seats when it is shut, thus bringing the same flush with the outer surface of the flange 13. The ribs of the side portions of the frame stop short of 55 the bottom thereof, to accommodate the lugs 17, and the lower ends of the ribs are beveled, as indicated at 22, against which beveled ends the upper ends of the lugs seat or 60 abut when the door is closed, said ends of the lugs being beveled to correspond to the bevel of the rib ends.

By reason of the oblong shape of the apertures 19, the door 15 will be thrown out of center when it is opened, and when it is 65 closed, it comes flush with the flanged margin of the frame 10. The hinges of the door are also entirely inclosed, and there are no projecting parts when the door is closed.

To the inner edge of the side walls 16, at 70 the top thereof, is secured, by angle irons 24, or otherwise, a cross-bar 25 projecting at its ends from the walls 16. One of the projecting ends of the cross-bar is in the path of a spring catch 26 mounted on the 75 corresponding side wall of the chute 14, on the inside thereof, and is engaged by said catch when the door is closed. When the door is swung open, the cross-bar strikes the ribs 20 on the side portions of the frame 80 10, thus limiting the outward swing of the door, and holding the same at a certain angle.

I claim:

1. The combination of a rabbeted frame 85 having oblong apertures in opposite side portions adjacent to the bottom, and a door mounted in the bottom portion of said frame between the side portions thereof and adapted to seat in the rabbet, said door having outstanding hinge pintles on its inner face on opposite sides working in the aforesaid apertures, said apertures being inclined in the direction of their greatest dimensions, and the inclination being toward the inner 90 portion of the frame.

2. The combination of a frame having a rib on the inside of its top and side portions

to form a rabbet, the rib on the side portions of the frame stopping short of the bottom thereof, and said side portions of the frame having hinge apertures located below the rib, a door seating in the rabbet, and lugs on the door, said lugs having outstanding hinge pintles working in the aforesaid apertures, and the lugs abutting against

the lower end of the rib on the side portions of the frame when the door is closed.

In testimony whereof I affix my signature in presence of two witnesses.

ALBERT RENTNER.
